MACHINE FOR INTERFOLDING STRIPS

Frederick R. Slavek, Woodside, Long Island, N.Y.

Application September 26, 1942, Serial No. 459,871

4 Claims. (Cl. 154—1)

This invention relates to machines for the production of doubled, re-enforced strips from thin, flexible, tape-like material, with particular reference to "Cellophane."

Such strips, or strands, in various colors, when braided or woven, form acceptable foundations for ornaments for women's hats, and other millinery uses, being waterproof, permanent in colorization, easy of application and moderate in cost of production.

It is an object of the invention to provide a mechanism which, progressively, places a relatively narrow lining or re-enforcing strip of dense material, as paper, midway between the side edges of the "Cellophane" strip, folds the edges thereover, refolds the combined strips, supplies an adhesive, and presses the sides together to complete cohesion.

A further feature is in the provision of means for adjusting and maintaining the paper liner strip centrally of the "Cellophane" strip, a condition that can be visually ascertained during progress of the operation, the strip serving to prevent light from passing through the translucent material in which it is enclosed.

Another purpose is to provide a novel means to apply an adhesive to the inner surface of one side only of the redoubled strips, in the exact quantity required, so that after seaming the sides, no excess adhesive appears, both edges being smooth and uniform throughout.

These and other advantageous aims are accomplished by the novel and practical construction, combination and arrangement of parts herein-after described, and illustrated in the accompanying drawing, constituting a graphical component of this disclosure, and in which:

Figure 1 is a plan view of an embodiment of the invention.

Figure 2 is a perspective view showing the fold-elements in greater detail.

Figure 3 is a transverse sectional view taken on line 3—3 of Fig. 2, drawn to an enlarged scale.

Figures 4, 5 and 6 are similar sectional views taken on corresponding lines of Fig. 2.

Figure 7 is a perspective view showing in detail a portion of the combined strips as they are advanced through the folding and adhering stages of the mechanism.

Figure 8 is a plan view of a piece of goods formed by braiding several of the strips together.

Referring to the drawing in detail, a bench, generally designated 15, forms the foundation of the mechanism, which, as shown, comprises two

fixed upright spindles 16, 17 on which reels 18, 19 respectively, are revolvably mounted.

The reel 18 carries a supply of "Cellophane" or like thin, pliable material 20, tape-like in form, having a glossy surface, preferably waterproof, in any preferred color and translucent in its nature.

The reel 19 is supplied with a liner strip 21, of opaque material, such as paper, of lesser width than the strip 20, of the same color and adapted to prevent penetration of light therethrough when the product is complete.

The mechanism is, however, not limited merely to two strands, casing and liner, as obviously a plurality of either may be employed.

15 The strip 20 is provided with a guide 22 adjustably mounted on the bench 15, while a similar guide 23 is mounted in like manner for the filler strip 21.

These guides are arranged to converge the strips just before they reach the flattened mouth of the first or initial, funnel folder 24, of well known type, but mounted floatingly on the flat face of a vertical bracket 25 secured on the bench.

20 A controller 26 is formed with a raised loop 27, open at its under side, adapted to engage over and around the contracted discharge portion of the folder 24 and by which it may be raised, lowered, turned at a slight angle and also moved lengthwise.

25 This is accomplished by reason of a longitudinal slot 28 in the controller shank, and a slot 29 in the bracket at a right angle thereto, through which passes a clamp bolt 30, whereby to retain the controller, together with the folder, in adjusted position.

30 Spaced in advance of the folder 24 is a final folder 31, fixed rigidly to the bracket 25, to receive the combined strips, the casing strip now having its edges turned inwardly, confining the liner therein.

35 It will now be apparent that the liner must be positioned centrally of the casing strip at the initial folding, see Fig. 7, which position is attained by proper adjustment of the controller; another feature, also accomplished by the controller, is that of spacing the folders sufficiently apart to permit a clear view of the relative positions of the casing and liner as they emerge from the initial folder and pass to the final folder, as at 32.

40 An adhesive container 33, mounted above the plane of the folders, has as a feeding means, a fibrous, brush-like wick 34 extending downwardly, its end engaging in a slot 35 in one of the side walls of the final folder, in a manner to apply an

even coating of the adhesive directly upon the inner surface of one side only, of the redoubled strip, just as it passes out.

The issuing strip enters between a pair of pressure rolls 36, 37, relatively upper and lower, by which the sides are closed and seamed, as at 38, in Figs. 2 and 7.

The upper roll 36 is fixed on a shaft 39 extending transversely across the bench and driven by a pulley 40, over which is trained a belt from any convenient power source.

Alongside the pulley 40 is a smaller belt pulley 41, driving a belt 42 trained over a sleeve pulley 43, frictionally engaged with a cone 44 fast upon a shaft 45; thus the shaft is frictionally, not positively, driven but may slip under excessive load.

The shaft 45 is mounted in bearings on the bench, parallel to the shaft 39, and has fixed upon it a drum 46; another similar drum 47 is mounted in bearings 48, 49 adjustable on the bench in such manner that the axes of these drums are at a slight angle, for the purpose of spacing the finished strip 38 as it is wound on the drums, after leaving the rolls 36, 37, so that the adhesive may be thoroughly dry and set.

Thereafter the strip is wound on a reel 50, fixed on a shaft 51 having a pulley 52, driven by a belt 53 from a pulley 54, on the main drive shaft 39.

Having thus described the invention, what is claimed as new and sought to secure by Letters Patent, is:

1. In a machine for making an interfolded strip from two strips of ductile material respectively inner and outer, comprising in combination, a funnel folder having an opening in one of its side walls adjacent the outlet thereof, a container for a liquid adhesive, a wick to conduct the adhesive from said container through the folder wall opening to deposit it on the inner surface of one of the upstanding sides of the outer strip prior to occlusion thereof, and a pair of rolls to press the sides of the strip into coherency when passed therebetween.

2. A machine for making a compound pliable strip of uniform width and thickness, comprising reels to supply individual casing and liner strips, said liner strip being of lesser width than the casing strip, an initial folder to turn the side edges of said casing strip over and upon the liner strip to partially encase the same, adjustable

means for guiding the strips to said initial folder, a final folder to complete folding the side edges of said casing strip, means to adjust said initial folder relative to the final folder laterally, longitudinally and angularly, and means to supply an adhesive to one of the inner side surfaces of the compound strip just prior to extrusion from said final folder.

3. A machine for making a ductile strip having uniform sides and edges, comprising a reel carrying a cover strip, a second reel carrying a liner strip of lesser width than the cover strip, a folder to turn the lateral edges of said cover strip over upon the liner, means to adjust the liner relative to the cover strip, a second folder for doubling the combined strip and liner, said second folder having an opening in one side near its outlet, a wick extending through the opening, means to supply said wick with an adhesive, compression rolls to squeeze the united sides of the strip, and a pair of drums over which the finished strip is wound, one of said drums being frictionally driven, the other loose and its axis obliquely inclined to the driven drum whereby the combined strip is coiled in spaced convolutions under moderate tension.

4. In a machine for making a compound pliable strip of uniform width and thickness, comprising reels to supply individual casing and liner strips, said liner strip being of lesser width than the casing strip, an initial folder to turn the side edges of said casing strip over and upon the liner strip to encase the same, adjustable means for guiding the strips to said initial folder, a final folder to complete folding the side edges of said strip, means to adjust said initial folder relative to the final folder laterally, longitudinally and angularly, wick means for coating one only of the inner surface of the side walls of the doubled strip just before extrusion from said final folder, positively driven compression rolls to consolidate the side walls of the strip after emergence from said final folder, a friction driven drum and a paired freely rotatable drum on which the strip is plurally coiled, said last named drum having its axis inclined with respect to the first named drum, and a driven reel to receive the completed strip.

FREDERICK R. SLAVEK.
